UNITED STATES PATENT OFFICE.

JOSEPH REISING, OF AURORA, ILLINOIS.

IMPROVED COUNTER-SUPPORTER.

Specification forming part of Letters Patent No. 59,075, dated October 23, 1866.

To all whom it may concern:

Be it known that I, JOSEPH REISING, of Aurora, in the county of Kane and State of Illinois, have invented a new and Improved Counter-Supporter for Boots and Shoes; and I do hereby declare that the following is a full, clear, and exact description thereof, which will enable others skilled in the art to make and use the same, reference being had to the accompanying drawings, forming part of this specification, in which—

Figure 1 represents a sectional side elevation of this invention when applied to the counter of a gaiter-boot. Fig. 2 is a horizontal section of the same. Fig. 3 is a perspective view of the same detached.

Similar letters of reference indicate like parts.

This invention relates to a counter-supporter which is provided with a bottom flange, and with a hole in its top end, in such a manner that the same can be firmly secured between the inner and outer sole, and also at its upper end to the counter, and that a supporter is obtained which effectually prevents the counter working on one side, keeping the same straight as long as the boot or shoe will last.

A represents my counter-supporter, which is made of steel or other suitable stiff and durable material, though I use steel by preference on account of its great strength. Said supporter is stamped or otherwise made, so that it fits nicely into the counter of a boot or

shoe, and it is provided with a bottom flange, *a*, and with a hole, *b*, in its upper end. The bottom flange *a* is introduced between the inner and outer soles of a boot or shoe, as shown in Fig. 1, and it is secured in its position by two nails or tacks, and the body of the supporter extends up on the inside of the counter and is secured to the same by a rivet passing through the hole *b*.

By this arrangement a counter-supporter is obtained which is held in position, first, by the pressure of the foot bearing down upon the bottom flange, and second, by the rivet passing through the hole *b*, and thereby the counter is effectually prevented from working off sidewise, or from becoming crooked, which happens with a great many boots or shoes, particularly such of boys and working-men, rendering the same useless before the other parts are worn out.

By the simple attachment of my supporter the counters are retained in their positions as long as the boot or shoe will last.

What I claim as new, and desire to secure by Letters Patent, is—

As a new article of manufacture, a steel counter-supporter, constructed as described, and applied to the rear portion of the heel, as and for the purpose specified.

JOSEPH REISING.
